UNITED STATES PATENT OFFICE.

JAMES F. NEEDHAM, OF HANFORD, WASHINGTON.

REFRIGERATOR.

Application filed May 18, 1922. Serial No. 561,956.

To all whom it may concern:

Be it known that I, JAMES F. NEEDHAM, a citizen of the United States, residing at Hanford, in the county of Benton and State 5 of Washington, have invented certain new and useful Improvements in Refrigerators, of which the following is a specification.

My invention relates to refrigerating means and has for its object the provision 10 of a structure or apparatus which will be efficient in reducing the temperature of a compartment without the use of ice. The invention is illustrated in the accompanying drawings and consists in certain novel features which will be particularly pointed out 15 in claims following the detailed description.

In the accompanying drawings—

Figure 1 is a perspective view of one embodiment of my invention; 20 Fig. 2 is a longitudinal vertical section of the same.

In the illustrated embodiment of the invention, there is employed a base 1 which may be of any material which will effectually resist the passage of heat. Upon this base, I erect a plurality of walls 2 and upon the walls I support a roof or cover 3 which, as shown most clearly in Fig. 2, comprises a top imperforate plate, a lower plate 25 4 having openings 5 therethrough, and connecting strips 6 whereby the upper and lower plates will be held in a fixed spaced relation. The connecting plates or rails 6 are disposed preferably longitudinally of the 30 structure, and across the ends of the roof are screened outlet openings 7 which provide an exit for the air from the interior of the refrigerator, the screens preventing the entrance of insects, as will be readily understood. One wall of the structure is provided with doors 8 to afford access to the interior and within the structure, upon the walls, are provided a plurality of cleats 9 which are adapted to support shelves 10 35 upon which may be placed articles of food. It may be noted at this time that the shelves are arranged with their ends spaced from the adjacent walls of the structure so as to afford circulation of air around the ends of the shelves, as will be readily understood 40 upon reference to Fig. 2.

In one end wall of the refrigerator, I form inlet openings 11 and through said openings I fit the tubular casing 12, the inner ends of which are open and unobstructed, while the outer ends are covered by

screens 13. Bars 14 are also secured across the outer ends of these tubular casings and these said bars support pipes 15 which are fitted within the tubular casings with spray nozzles 16. The pipes 15 are coupled to a supply pipe 17 which extends to any convenient or preferred source of supply. The source of supply may be a spring or other water source or it may be a tank within which an ice or other refrigerant has been placed. It is to be understood, of course, that where ice is available, the air supplied to the refrigerator will be reduced to a lower temperature than is ordinarily possible with the use of water alone but the apparatus operates efficiently where ice is not available. The tubular casings 12 terminate within the refrigerator slightly beyond the wall in which they are mounted and, beyond the discharge ends of these tubular casings, curtains 18 of canvas or other fabric are suspended in the path of the water issuing from the casings. I prefer to employ two of these tubular casings with a curtain in 50 front of each casing, as shown in the accompanying drawings, one of the curtains being located between the bottom of the refrigerating compartment and the first shelf while the other curtain is located between 55 the first and second shelves. The first shelf may well be, and is illustrated as, a shallow tray 19 from the end of which more remote from the curtain depends a drain 20, a second drain 21 leading from the bottom of 60 the refrigerator through the end wall thereof to the exterior. This drain 21 may carry the water to any point of discharge or may be connected with pipes by which it is returned to the source of supply. The curtains 18 are illustrated as secured across the 65 ends of interior housings 22, but this particular arrangement is not essential, it being sufficient if the screens are suspended in any manner beyond the ends of the casings 12 but sufficiently close to said casings to extend across the path of the water and air issuing from the same.

In the use of the device, water is admitted to the nozzles 16 through the pipes 17 and 70 15 and will issue from the nozzles in a fine spray. As the outer ends of the casings 12 are open to the air, air will be drawn in through the casings by the flow of the water and will be commingled with the water so 75 that it will be very effectually cooled. The parts are so proportioned that the spray dis-

charged by the nozzles 16 will cover the entire cross sectional area of the tubular casings and, consequently, the air will be thoroughly commingled with the water so that 5 the heat of the air will be nullified. The spray will have sufficient force to impinge against the curtains 18 which act as condensers to further agitate the air and water and prevent the water spreading upwardly 10 within the refrigerator compartment. The water will, of course, saturate the curtains and will seep through the same and flow toward the drains 20 and 21 while the air liberated from the water and reduced in temperature will rise past the several shelves 15 5 and the screened ends 7. I thus maintain an effectual circulation of a cooling medium through the refrigerator so that, after food 20 is placed therein, it will be preserved for a considerable period and any foul odors which may arise within the refrigerating compartment will be carried out and will be prevented from collecting therein.

25 While my invention is intended more particularly for stationary structures, it may be portable. When stationary, I preferably construct the base and walls of concrete, but in the portable form they may be of wood 30 lined with metal or of any other suitable material. It may be very advantageously employed to effect a pre-cooling of refrigerator cars in which soft fruit or vegetables are to be transported. When employed for this 35 purpose, it is desirable to pass the water through a chamber containing ice before admitting it to the spray nozzles inasmuch as the temperature of the car may be thereby more quickly and thoroughly lowered. The 40 device is very simple and compact in the arrangement and construction of its parts and may be installed without employing highly skilled labor.

Having thus described the invention, what 45 is claimed as new is:

1. A refrigerator comprising a plurality of walls, a hollow roof supported upon the walls having an imperforate top and pro-

vided with outlet openings through its bottom, screened outlets at the ends of the roof, 50 an open-ended tubular casing extending through one wall of the refrigerator to admit air to the interior of the refrigerator, a spray nozzle located within said casing arranged to discharge into the refrigerator, means for supplying water under pressure to said nozzle, and a condensing curtain suspended 55 within the compartment in the path of the fluid discharging from the said casing.

2. A refrigerator comprising a plurality 60 of walls, a hollow roof supported on the walls and having an imperforate top and provided with outlet openings through its bottom, screened outlets between the top and bottom of the roof, an open-ended tubular 65 housing extending through a wall of the refrigerator near the bottom thereof and having a foraminous outer end to admit air through the housing to the interior of the refrigerator, a water supply pipe entering 70 said housing, a spray nozzle on the end of said pipe within the housing arranged to discharge into the refrigerator, a condensing curtain suspended within the refrigerator across the inner end of the housing, shelves 75 supported within the refrigerator above the housing and the condensing curtain in spaced relation to the walls of the refrigerator, and a drain remote from the housing and the condensing curtain.

3. A refrigerator comprising essentially 80 imperforate walls, a hollow roof supported on the walls and provided with outlets between its top and bottom, an open-ended casing fitted through one wall near the bottom thereof, a spray nozzle in said casing directed toward the inner side of the wall, means for supplying water under pressure to 85 said nozzle, a fabric curtain suspended across the inner end of said casing in spaced relation thereto, and means for carrying off water of condensation from the curtain, the liberated cool air rising to and escaping 90 through the hollow roof.

In testimony whereof I affix my signature. 95
JAMES F. NEEDHAM. [L.S.]
